REFRIGERATING APPARATUS

Sylvester M. Schweller, Dayton, Ohio, assignor,
by mesne assignments, to General Motors Corporation,
a corporation of Delaware

Application April 25, 1932, Serial No. 607,327

9 Claims. (Cl. 62—103)

This invention relates to refrigerating apparatus and more particularly to provisions for utilizing space in mechanically refrigerated cabinets for the storage of foods, which space was heretofore unavailable or unsuited for such purpose.

It is well-known that a cooling unit, of a mechanical refrigerating apparatus located within a compartment or cabinet to be cooled, collects moisture from air circulated in the compartment by the cooling effect produced by the evaporator of the apparatus. This moisture collects in the form of frost or ice upon the cooling unit and during certain cycles of operation of the refrigerating apparatus or when a large quantity of food products, to be cooled, are placed in the refrigerator cabinet a slight thawing or melting of this frost or ice occurs. Considerable or complete thawing or melting of the frost or ice accumulated on the cooling unit also occurs when operations of the refrigerating apparatus or system are interrupted, for the purpose of defrosting the cooling unit, and causes the water, resulting from such thawing or melting, to drip or flow from the cooling unit. In installations of mechanically refrigerated cabinets where a drain has not been accessible it has been customary to provide a drip pan or receptacle, to be disposed below the cooling unit or evaporator, with each refrigerator cabinet. This pan or receptacle has been constructed so as to be of sufficient capacity to contain or collect water dripping from the evaporator not only during the slight or temporary thawing or melting periods of the evaporator but also during complete defrosting of the evaporator. Consequently this pan or receptacle necessarily occupied valuable space or more space in the refrigerator than required during normal or uninterrupted operation of the refrigerating apparatus.

An object of my invention is to provide means for collecting the drip from a cooling unit during normal operation of the refrigerating apparatus or system which means has additional auxiliary storing capacity for collecting drip from a cooling unit during complete defrosting thereof, and to utilize this additional storing capacity of the drip collecting means for the storage of comestibles or food products.

In carrying out the foregoing object it is a further object of my invention to permit one portion of the drip collecting means to be removed from the other portion thereof and from beneath the cooling unit in a refrigerator cabinet without removing the other or auxiliary storing ca-

pacity or portion of the means and comestibles contained therein.

Further objects and advantages of the present invention will be apparent from the following description, reference being had to the accompanying drawing, wherein a preferred form of the present invention is clearly shown.

In the drawing:

Fig. 1 discloses a refrigerator cabinet of the household type having a drip collecting means 10 constructed in accordance with the present invention disposed beneath the cooling unit mounted in the cabinet;

Fig. 2 is a fragmentary enlarged view of the refrigerator cabinet disclosed in Fig. 1 showing 15 the drip collecting means in cross-section;

Fig. 3 is a vertical sectional view of the refrigerator cabinet taken on the line 3—3 of Fig. 2;

Fig. 4 is a view similar to Fig. 2 showing a modified form of drip collecting means 20 constructed in accordance with the present invention disposed below the evaporator; and

Fig. 5 is an enlarged fragmentary vertical sectional view of the modified form of drip collecting means shown in Fig. 4 and taken on the line 25 5—5 thereof.

Referring now to the drawing for the purpose of illustrating my invention I have shown in Fig. 1 thereof a refrigerator cabinet 10 of the household type including a food storage compartment 11 and a machine compartment 12. The food storage compartment 11 has a door 14 pivotally mounted to cabinet 10, shown in open position, for closing the open front of the food compartment. The machine compartment 12 is closed by a door 15. An evaporator or cooling unit 16 of any suitable form is mounted in any desired manner in the compartment 11 preferably in the upper portion thereof. The evaporator 16 includes the usual ice trays 17 adapted to receive water to be 30 frozen. Evaporator 16 is connected in a closed circuit with a refrigerant liquefying unit (not shown) and ordinarily disposed in the compartment 12. Shelves 19 mounted in any suitable manner such as on pegs 21 divide the interior of the compartment 11 of cabinet 10 into a plurality of food storage sections.

Since the evaporator of a mechanically refrigerated cabinet collects moisture as hereinbefore pointed out, which moisture freezes on the evaporator in the form of frost or ice and then thaws or melts, when a large supply of foods are placed in the compartment to be cooled or, during certain periods or cycles of operation of the refrigerant liquefying unit of the system it is necessary 35 40 45 50 55

to provide some means for collecting the water, resulting from such thawing or melting, and preventing this water from flowing onto combustibles or food products stored in the compartment 11 5 below the evaporator 16. Such means is also particularly essential in a refrigerator cabinet including an evaporator which receives ice trays containing water to be frozen since water is frequently splashed or spilled from the trays during 10 insertion thereof in the cooling unit. Therefore I have provided a drip collecting means 25 for this purpose. The drip collecting means 25 includes a receptacle pan or dish 26 having a lid or cover 27 peripherally supported thereon and 15 movable therefrom. The lid or cover 27 has its bottom wall depressed as at 28 to form a tray or reservoir. An opening 29 is provided in the lid or cover 27 by punching or cutting a hole in the depressed portion 28 thereof. The metal adjacent 20 the opening 29 is formed upwardly in any suitable manner so as not to destroy the reservoir provided by the depressed portion 28 of the lid or cover. Lid or cover 27 has its outer or peripheral edge flanged upwardly as at 31. The inlet to 25 opening or outlet 29 in lid 27 is arranged slightly below the up-turned top edge of flange 31. Thus the reservoir portion of lid 27, formed by the depression 28, serves as a tray for receiving and collecting drip water from the cooling unit or evaporator 16 during normal operation of the refrigerating apparatus or while the apparatus is in operation to cause the evaporator to produce refrigeration as hereinbefore pointed out. The receptacle or pan 26 serves as an auxiliary reservoir or tray for receiving and collecting drip water from the evaporator or cooling unit when operations of the refrigerating apparatus are interrupted such, for example as when the refrigerating apparatus is rendered inoperative over an 30 indefinite period of time to cause complete defrosting of the cooling unit.

The tray or reservoir formed in lid 27 being of ample capacity to store drip water from the evaporator during normal operation of the refrigerating system therefore permits utilization of the auxiliary receptacle or dish 26 for the storage of 45 comestibles such as meats or the like at all times except when the cooling unit 16 is to be completely defrosted. Thus storage space provided in dish 50 26 below the lid 27 ordinarily not used or unsuitable for use and which space is very valuable in household refrigerators, particularly refrigerator cabinets of the apartment type is rendered available without danger of contaminating foods 55 placed therein as long as the refrigerating apparatus is operating. Sufficient clearance is provided between the bottom of the cooling unit 16 and the drip collecting means 25 to permit the lid or cover 27 to be removed from the cabinet 10 or 60 compartment 11 to empty the lid 27 of its water content. This lid 27 may be removed from compartment 11 without removing the entire drip collecting means 25 and consequently without disturbing foods stored in the dish or auxiliary reservoir 26. When it becomes necessary to 65 completely thaw or defrost ice or frost accumulated on the cooling unit, foods contained in the dish 26 may be removed therefrom and temporarily placed in another portion of the compartment 11. 70 Water resulting from defrosting of the evaporator flows therefrom into the lid 27. This water upon rising in reservoir 27 above the inlet to outlet 29 then flows into the auxiliary reservoir or dish 26 of the drip collecting means 25 which may be of 75 ample capacity to store water resulting from one

or more defrosting operations. If desired the lid 27 may be omitted from the drip collecting means 25 during defrosting of the evaporator. Since 5 relatively large pieces of ice frequently drop from the evaporator 16, during defrosting thereof, it is preferable to relocate the lid 27 upon the dish 26 after foods contained in the dish have been removed therefrom and the apparatus rendered inoperative to defrost the evaporator. This lid 27 being capable of containing or storing only a 10 shallow body of water thereby reduces splashing of water, by falling pieces of ice, from the drip collecting means.

In the modified form of my invention disclosed in Figs. 4 and 5 of the drawing the drip collecting means 25 includes provisions for rendering the inlet to the outlet 29a of lid 27a adjustable. As shown in Fig. 5 of the drawing the inner wall of the up-turned metal of lid 27a forming the outlet 29a is threaded as at 32. A hollow nut 33 20 is threaded upon the threads 32 and the inlet to the hollow nut 33 or to the outlet 29a may be raised or lowered relative to the top surface of lid 27a. This modified form of my invention insures that the drip water from evaporator 16 25 will not flow into the auxiliary reservoir formed by dish 26a when foods are stored therein. For example, if foods are placed in the dish 26 or 26a which foods will be damaged or spoiled by contact thereof with water the nut 33 may be 30 adjusted upon the threads 32 so that its inlet is on a higher plane than the top edge of flange 31a. Should defrosting of the evaporator occur while the nut 33 is in the upper position as described 35 the drippage from the evaporator will flow into the lid or tray 27a and will rise above the top edge 31a thereof and overflow therefrom and pass downwardly on the exterior walls of the dish 26 or 26a. The foods stored in dish 26 or 26a 40 which may be of an expensive variety are thereby protected from being damaged by contact with water.

It is to be understood that the lid 27 or 27a 45 may be designed to fit snugly throughout its peripheral contact with dish 26 or 26a, or it may have depressions or indentations of suitable size formed therein around the portions immediately adjacent the dish 26 to provide a predetermined amount of air circulation between the interior of the dish 26 or 26a and the food storage compartment 11 in addition to that afforded by the opening 29 or 29a in the cover 27 or 27a. The dish 26 or 26a may also be provided with openings or holes in the walls thereof for this purpose. Thus the drip catching means 25 may be utilized 55 as a hydrator for the storage of vegetables and the like, if desired.

From the foregoing it is apparent that I have provided an improved refrigerating apparatus or refrigerator cabinet of the household type in 60 which space heretofore unavailable or unsuited for use is now utilized for the storage of foods. Since refrigerators of the present day vary in cost principally with respect to the amount of food storage capacity therein my invention 65 becomes of paramount importance. My invention permits this added food storage space to be had in existing refrigerator cabinets, equipped with drip pans or dishes, as well as those to be hereafter sold.

While the forms of embodiments of the invention as herein disclosed constitute preferred forms, it is to be understood that other forms might be adopted, all coming within the scope of 70 the claims which follow.

What is claimed is as follows:

1. The combination with a mechanically refrigerated cabinet including a compartment having a cooling unit of a refrigerating system mounted therein, a food storage receptacle, a tray removably supported on and forming a cover for said receptacle, said receptacle and cover being so positioned within the refrigerator compartment that the drip water from the cooling unit is received by said tray, and means for directing the drip water from said tray to said receptacle.
2. The combination with a mechanically refrigerated cabinet including a compartment having a cooling unit of a refrigerating system mounted therein, a food storage receptacle, a relatively flat lid removably supported on said receptacle and having a depression formed therein, said receptacle and lid being so positioned within the refrigerator compartment that the drip water from the cooling unit is received by said depression, and means for directing the drip water from the depression in said lid to said receptacle.
3. The combination with a mechanically refrigerated cabinet including a compartment having a cooling unit of a refrigerating system mounted therein, a food storage receptacle, a relatively flat lid removably supported on said receptacle and having a depression formed therein, said receptacle and lid being so positioned within the refrigerator compartment that the drip water from the cooling unit is collected in said depression, said lid having an outlet formed therein communicating with said receptacle, and the inlet to said outlet being disposed between the bottom and the top of said lid.
4. The combination with a mechanically refrigerated cabinet including a compartment having a cooling unit of a refrigerating system mounted therein, a food storage receptacle, a relatively flat lid removably supported on said receptacle and having a depression formed therein, said receptacle and lid being so positioned within the refrigerator compartment that the drip water from the cooling unit is collected in said depression, said lid having an outlet formed therein communicating with said receptacle, and means for moving the inlet to said outlet above or below the top edge of said lid.
5. The combination with a mechanically refrigerated cabinet including a compartment having a cooling unit of a refrigerating system mounted therein, a food storage receptacle, a relatively flat lid removably supported on said receptacle and having a depression formed therein, said receptacle and lid being so positioned within the refrigerator compartment that the drip water from the cooling unit is collected in said depression, said lid having an outlet formed therein communicating with said receptacle, and means for moving the inlet to said outlet above or below the top edge of said lid.
6. The combination with a mechanically refrigerated cabinet including a compartment having a cooling unit of a refrigerating system mounted therein, a food storage receptacle, a relatively flat lid removably supported on said receptacle and having a depression formed therein, said receptacle and lid being so positioned within the refrigerator compartment that the drip water from the cooling unit is collected in said depression, said lid having an outlet formed therein communicating with said receptacle, said outlet being threaded, and an adjustable hollow plug threaded upon the threaded portion of said outlet for moving the inlet to said outlet above or below the top edge of said lid.
7. The combination with a refrigerator cabinet including a compartment having a cooling unit of a refrigerating system disposed therein, a substantially closed container disposed below and in spaced relation to said cooling unit within the refrigerator compartment, a flange extending upwardly from the top of said closed container providing a receptacle for receiving drip water from said cooling unit, conduit means for conducting the drip water from said receptacle to said container, and said container being removable from said refrigerator compartment while said cooling unit is positioned therein.
8. The combination with a refrigerator cabinet including a compartment having a cooling unit of a refrigerating system disposed therein, a receptacle within the refrigerator compartment, a cover for said receptacle, said cover being so positioned within the compartment relative to said cooling unit that drip water from the unit is received thereby, and conduit means for directing drip water received by the cover into said receptacle.
9. The combination with a refrigerator cabinet including a compartment having a cooling unit of a refrigerating system disposed therein, a receptacle within the refrigerator compartment, a cover for said receptacle, said cover being so positioned within the compartment relative to said cooling unit that drip water from the unit is received thereby, and conduit means for directing drip water received by the cover into said receptacle, said receptacle being removable from said refrigerator compartment and said cover being removable relative to said receptacle.

SYLVESTER M. SCHWELLER.
